UNITED STATES PATENT OFFICE

2,527,012

PORTABLE HOUSE

Clarence William Kinsman, New York, N. Y.

Application June 21, 1947, Serial No. 756,231

3 Claims. (Cl. 280—80)

1

This invention relates to portable houses and has for its object the provision of a two-story portable house having a demountable roof and demountable wheels which is adapted to be constructed at an assembly point and to be moved to a building site for temporary or permanent location upon a foundation.

Another object is to provide a small-sized two-story dwelling having a demountable roof and demountable front and rear wheels adapted to be readily transported or moved along the usual type highways for temporary or permanent location on a building site.

A further object is to provide a relatively inexpensive portable house to meet the present housing emergency.

Other objects will be apparent as the invention is more fully hereinafter disclosed.

In accordance with these objects I have designed a portable house which is primarily adapted to meet quickly and economically the present housing shortage, insofar as that shortage can be met for small sized families and by the provision of the essential living space therefor. The portable house of the present invention is designed for mass construction at a central manufacturing point and for towing transport over the standard sizes and types of roads and highways found in settled areas, such as large civic centers, for delivery to a building site whereon it may be quickly and economically set upon a temporary foundation and connected to the usual utilities for prompt occupation by the owner or renter thereof.

In its briefest definition the present invention consists of a base frame upon which the house is constructed to a story and a half height with a demountable roof thereon to complete a two-story structure, which base frame is supported and reinforced by a chassis having demountable rear wheels and a detachable and guidable front wheel assembly, said front wheel assembly being arranged for attachment to a towing prime mover, such as a truck or tractor for guided transport along the road or highway, all as will be more fully hereinafter described.

The invention may be widely varied and modified without essential departure therefrom, as one skilled in the art will perceive. In the drawings, I have shown by way of illustration and not by way of limitation, as one specific embodiment of the invention, a practical type of small portable house which may later be adapted for use as a garage.

In the drawings:

Fig. 1 is a side view of the portable house of the present invention as it appears ready for occupancy when located on a foundation at a building site, with the demountable roof in place and the demountable wheels removed;

2

Fig. 2 is a front view of the same;

Fig. 3 is an interior view along plane 3—3 of Fig. 9 looking towards the front of the house;

Fig. 4 is a framing view illustrating the constructional features of the demountable roof;

Fig. 5 is an enlarged sectional view taken along plane 5—5 of Fig. 9 illustrating the features of the demountable rear wheels;

Fig. 6 is an enlarged sectional view along plane 6—6 of Fig. 3 showing the details of the demountable rear wheels;

Fig. 7 is an enlarged sectional view taken along plane 7—7 of Fig. 9 illustrating the structural features of the base or frame of the building and chassis support and reinforcement thereof;

Fig. 8 is a sectional view along plane 8—8 of Fig. 3 illustrating the constructional features of the second floor of the building.

Fig. 9 is a sectional view along plane 9—9 of Fig. 3 illustrating the structural features of the base or frame of the building and the demountable front and rear wheels thereon;

Fig. 10 is a sectional view along one side of the building frame at about the level of plane 10—10 of Fig. 3;

Fig. 11 is a sectional view taken at about the level of plane 11—11 of Fig. 3, showing the frame structure and interior arrangement of the building;

Fig. 12 is an enlarged top view of the removable front wheel assembly;

Fig. 13 is a sectional view of the same taken along plane 13—13 of Fig. 12;

Fig. 14 is a front view of the same; and

Fig. 15 is a view illustrating the manner of attachment of the removable front wheel assembly to the chassis and base frame of the building.

As may be noted from the drawings the invention provides a two-story house with a demountable roof and with demountable and removable front and rear wheels secured to the chassis supporting and reinforcing the base frame of the house, the front wheels being arranged for guided towing of the structure by a prime mover, such as a truck.

The house frame and the arrangement of the house interior by partitions, etc., may be widely varied without departure from the invention. In its broadest aspect the invention contemplates the provision of a base frame mounted upon and reinforced by a steel chassis to which may be demountably attached or secured rear wheels and guidable front wheels arranged for towing movement of the base frame with house mounted thereon; and for the construction on the base frame of a story and a half house complete in substantially all details with a demountable roof thereover completing the second story of the house. The shape of the

roof and its sectioned arrangement may be widely varied without departure from the invention. Upon delivery to the building site, the portable house then requires only the seating of the same upon a suitable foundation, by wheel deflation; the connecting of the utilities of gas, water, sewer, and electricity thereto; the securing of the demountable roof sections in place; and the removing of the demountable wheels; to be ready for occupancy.

Referring now to the drawings for specific details of the invention in Figs. 1 and 2 is shown the house H with demountable roof R in place seated upon foundation F on the building site ready for occupancy.

In Fig. 3 is shown the interior and structural features of the house H prior to seating the same upon the foundation F after the demountable roof R has been positioned in place thereon.

Referring now to Fig. 9, which is a view taken along the plane 9—9 of Fig. 3 at a level just below the floor f, the details of the reinforced base frame B upon which the house H is constructed may be noted.

The base frame B consists of a rectangular base comprised of wood supported on and reinforced by steel channel members C—C' extending the full length of the base on opposite sides thereof and extending beyond the front of the base, at an angle inclined towards each other from a point rearwardly the front of the base, a sufficient distance to permit attachment thereto of the front wheels in a guidable mounting, as will be more fully hereinafter described.

The particular construction of base frame B and the manner of mounting or supporting the same upon steel channel members C—C' may be widely varied without essential departure from the invention as one skilled in the art will readily recognize. The essential requirements in this combination is that the base frame B is constructed and reinforced in such a way as to provide a substantially rigid platform or base upon which the house H may be raised; and that the steel channel members C—C' are of such strength and rigidity as to carry the weights of the base B with the house H thereon; and that the manner of attachment of the rear and front wheels thereto shall provide reasonable flexibility or spring action sufficient to absorb the shocks and vibration incident to transporting the structure over somewhat uneven but not rough ground.

These requirements are met in the assembly illustrated. The base frame B consists of an outer frame, the opposite sides of which consist of overlapping beams 1—2 (Fig. 7) with the channels C—C' secured to one beam 1 and supporting the other beam 2 with the normal sill 3 laid on top of the base frame B and the overlap space between sill 3 and beam 1 being filled in by a spacer board 4 to provide a firm foundation for the sill 3. As an example of this construction wooden beams 1 and 2 are each 3" x 12" spoked or bolted together with a 4" overlap; channel C is a 4" channel (4" x 3" x 3") seated in the under overlap of beams 1 and 2 and bolted to beam 1 at a plurality of points over its length; sill 3 is a 2" x 4" beam; and spacer board 4 is 1" or 2" x 4".

Channels C—C' provide rigid support for the opposite sides of base B and cross-beams 5 having their opposite ends seated within channels C—C' provide means to locate the opposite sides in the desired parallel spaced relation.

Channels C—C' at a point rearwardly the front end of the base frame B are each bent inwardly at an angle which, if projected beyond the front end of the base frame B, would bring them together at a point approximating the longitudinal center line of the building, but each channel C—C' terminates a short distance beyond the front end of the base frame B as indicated in Figs. 1 and 2.

10 The front end of the base frame B is completed by a construction similar to that described above for the opposite sides of the frame, with the front end beam 1 cut sufficiently to permit the channels C—C' to extend therethrough. The rear end is completed in any manner suitable to the required strength and appropriate to the purposes desired; and to provide for a door for entry into the building.

15 Flooring joists 5 and 6 are located substantially as indicated in Fig. 9, with the ends thereof carried within and supported by the channel members C—C' insofar as possible and held therein in determined spaced relation by spacer members 10. Floor joists 7—7' on opposite sides of channels C—C' as the channels angle inwardly are supported on beams 8—9 and 8'—9', respectively, which are spiked to the base frame B in proper position.

20 Such a base frame construction is rigid and of sufficient weight-carrying capacity to support thereon the story and a half structure indicated in Fig. 3.

25 Rear wheels W—W are mounted on base frame B to support and carry the base frame B with house H thereon, preferably in such manner as to be readily demountable, as indicated in Figs. 9, 5 and 6. Referring to these figures, it will be seen that each wheel W is a pneumatic tire type wheel having a balloon tire 11 seated 30 on a rim 12 forming the periphery of a disc or other type wheel having a hub 13 within which is located a roller bearing 14, through which extends an axle 15, the opposite ends of which are mounted on channel C and on cross-beams 16, respectively.

35 The particular mounting provided for rear wheels W—W may be widely varied without essential departure from the present invention. In the arrangement shown in the drawings, a bearing plate 17 is located by bolts 18—18 across the open face of channel C in which plate 17 is provided a bearing opening through which extends axle 15 into a recess 19 in beam 2 of the base frame B. The opposite end of axle 15 is held in position on top of cross-beams 16 by clamp means 20, substantially as indicated. If desired, channel C may be filled with a reinforcing filler-bar 21. This arrangement locates the wheel axle 15 at a horizontal level above the floor f of the base frame B in a position to be readily detached from the base frame B after the base frame has been located in position upon a foundation F, the opening thus left in the floor f being closed by a floor panel fitting the opening.

40 Front wheels W'—W' are detachably mounted on the extending ends of channels C—C' in an arrangement providing for guided towing of the assembly, substantially as indicated in Figs. 12 to 15, inclusive. Referring to these figures, it will be noted that each extending end of channels C—C' is provided with a plurality of bolt-holes 30 aligned horizontally therein. Heavy steel side plates P—P' are provided, each having a corresponding plurality of bolt-holes 31 aligned 45 horizontally in the bottom area thereof for

mounting the plates P—P' upon the extending ends of channels C—C', to form a vertical projection of the channels C—C' to a horizontal level just below the bay window E of house H. Channels 32—32 are bolted to the upper inside face of plates P—P' to reinforce same and to project the channels C—C' to their intersection at the horizontal level of the upper edges of plates P—P' where they are secured together. Cross-bar 33 is provided between channels 32—32 to prevent lateral spreading of plates P—P' and channels 32—32 and to provide a rigid projection of channels C—C'.

Upper and lower bearing plates 34—34' are secured in position above and below the forward meeting ends of channels 32—32, on which bearing plates are secured bearings 35—35' through which extends rotatable shaft S on the off-set end of which shaft S the forward wheels W'—W' are rotatably mounted, in bearings 40—40'. This arrangement is a typical caster mounting for wheels W'—W'. However, the upper end of shaft S is provided with a guide or steering sprocket wheel 36 connected by sprocket chain 37 to hand steering wheel 38 mounted on cross-bar 33 through an opening provided in the bottom of bay window extension E of the house H under which the assembly extends.

Bail 41, pivotally mounted through openings 42—42' in plates P—P' in channels 32—32, is provided to provide for the application of towing power to the forward end of the assembly by some prime mover, such as a truck or tractor, through a link 43.

As hereinabove indicated, the precise house structure constructed on base frame B may be widely varied without essential departure from the invention. In the drawings a relatively simple house structure is shown which is essentially one of a story and a half in height provided with a detachable roof R completing the height of the second story. The house H is indicated as having a first floor (Fig. 10) with a large living room and kitchenette and with a stairway 50 going up to the second floor. The second floor is indicated (Fig. 11) as having a large bedroom 51, a bath 52, and closets 53 and 54. Various alternative floor plan arrangements are possible of the floor space provided without departure from the invention.

For portability along standard roadways in populated areas, such as large civic centers, I have arbitrarily set a dimension limit for the base frame B of 10 feet 6 inches in width and 21 feet 0 inches in length and a story and a half height of 14 feet as being the most practical dimensions. On this size of house H, I provide a demountable roof which when in place adds another 5 feet 6 inches to the height of the building to provide ample headroom over the second story of the building.

The demountable roof R, as indicated in Fig. 4, is preferably built in sections or panels, each adapted to be bolted together to form the complete roof which may be removably secured in position upon the house H. Many different designs of roofs and roof panels are utilizable in the present invention, as one skilled in the art will recognize. Suitable openings 55—55' may be provided in the roof R for chimney and sewer vent pipes to extend therethrough. The roof R may be a plain roof or a gabled one as shown in the drawings, without departure from the invention.

To facilitate the setting of the house H in position upon a foundation F, all of the facilities, such as sewer, water, gas and electricity, are arranged to enter the house H at one end and close together so that these connections may be made with ease by one skilled in the art. Various means for heating the house interior are available and, per se, forms no part of the present invention.

It is believed apparent from the above disclosure that the invention may be widely modified without essential departure from the invention and all such modifications and departures therein are contemplated as may fall within the scope of the following claims.

15. What I claim is:

1. A portable house comprising in combination, a rectangular base frame, a house structure mounted on said base frame, a chassis supporting and reinforcing opposite sides of said base frame, said chassis extending beyond one end of said base frame, a guidable front wheel assembly demountably secured to the extending end of said chassis, a pair of rear wheels, and means for separately and detachably securing the wheels to the chassis and base frame in transverse alignment under the base frame.
2. A portable house comprising in combination, a rectangular base frame, a house structure mounted on said base frame, a chassis consisting of a pair of metal girders running the length of the base frame adjacent each side thereof and extending beyond one end of the base frame and secured to the underside of the base frame, a guidable front wheel assembly demountably secured to the extending ends of said girders, a pair of rear wheels and means separately and demountably securing the said wheels to the chassis and base frame in transverse alignment.

3. A portable house comprising a rectangular base frame consisting of side and end beams and floor supporting cross-beams, a house structure mounted on said base frame, said structure having a height of one and one-half stories and having a demountable roof, a pair of metal girders secured to the underside of the base frame and to the side beams of the base frame and having a length providing identical lengths thereof extending beyond one end of the base frame, a guidable front wheel assembly demountably secured to the extending ends of said girders, a pair of rear wheels, and means separately securing the said wheels in transverse alignment said means for each wheel providing a demountable connection to the base frame and to a girder to rollably sustain the base frame and house structure mounted thereon.

CLARENCE WILLIAM KINSMAN.
